UNITED STATES PATENT OFFICE.

THOMAS P. JORDAN, OF DALLAS, TEXAS, ASSIGNOR TO E. H. CARY, OF DALLAS, TEXAS.

PHANTOM TELEPHONE SYSTEM.

No. 838,028.

Specification of Letters Patent.

Patented Dec. 11, 1906.

Application filed October 3, 1904. Renewed December 20, 1905. Serial No. 292,588.

To all whom it may concern:

Be it known that I, THOMAS P. JORDAN, a citizen of the United States, residing at Dallas, Texas, have invented a Phantom Telephone System, of which the following is a specification.

This invention relates to a system of transmission of electrical energy, and more particularly to telephones; and the object is to produce telephone-circuits more economically than can be done with any known system of telephones by providing devices by which superposed or phantom circuits may be established by which a number of conversations can be carried on simultaneously on the same circuits without interference and by which devices a point of zero-potential can be detected or established or shifted.

In multiplex telephony many attempts have been made to carry on simultaneously a number of conversations by establishing superposed or phantom circuits. So far as known all such attempts have been failures.

In combined telephone and telegraph lines a system in ordinary use comprises an all-metallic telephone-circuit provided at each end with the usual transmitting and receiving instruments, and a telegraph-circuit is established by connecting a short line at each end of the telephone-circuit at a point of zero-potential, both wires of the telephone system being used in parallel on the telegraph-line and the opposite half of the line being formed by the ground. A circuit of this kind may be successfully used, as the impedance of the telegraph instruments or of auxiliary resistance located in the short line will prevent grounding of the telephone-circuit. Attempts have been made to utilize a similar system for multiplex telephony, a transmitter and a receiver taking the place of the key and sounder and connected inductively to the main line. Attempts have also been made to establish phantom circuits by connecting two all-metallic telephone-circuits by a line bridging between the points of zero-potential on each and to which auxiliary telephone sets are inductively connected. So far as I am aware, however, these attempts have not been successful from a practical standpoint, owing to lack of balance of the line, inasmuch as the electrical properties of the all-metallic circuit forming one leg of the superposed circuit would differ from the elec-

trical properties of the all-metallic telephone-circuit forming the opposite leg. These differences are due in part to differences in the length of the lines, to differences in the resistance, self-induction, or disturbance due to the passage of currents of difference of character on adjacent lines to which either circuit may be inductively related.

One of the objects of the present invention is to provide a superposed or phantom circuit in which provision is made for gradually balancing the lines with reference to locals of the main circuit and establishing a zero-potential to form the point of connection with the bridging-wire forming the phantom circuit.

A still further object of the invention is to provide such an improved balancing means which may be gradually adjusted to accommodate varying conditions.

Other objects and advantages will be fully explained in the following description, and the invention will be more particularly pointed out in the claims.

Reference is had to the accompanying drawings, which form a part of this application and specification.

Figure 1 is a diagram of a telephone-circuit arranged in accordance with the invention, illustrating a superposed or phantom circuit formed by connecting two all-metallic telephone-circuits. Figs. 2 and 3 are similar views illustrating slight modifications of the ways of wiring. Fig. 4 is a detail view of the adjustable balancing means. Fig. 5 is a similar illustration to that shown in Fig. 1, but shows a multiple connection instead of the series connection shown in Fig. 1. Fig. 6 illustrates a multiple connection with one movable spool for the balancing means.

Similar characters of reference are used to indicate the same parts throughout the several views.

The apparatus will be described in detail, and then the differences between the multiple and series connection will be pointed out and some of the advantages of the multiple connection explained.

In Fig. 1, A, B, C, and D designate four stations, at each of which is a transmitter 1, a battery 2, and an induction-coil 3, all of the usual construction and the primary of the coil being connected to the battery. The transmission is made in the ordinary manner.

The secondary 4 includes an ordinary form of receiver 5 and is arranged in inductive relation to the main line connecting the stations. Between stations A and B extend 5 main lines 6 and 7, and between stations C and D extend main lines 8 9. The connection between each secondary and the main line is formed by induction-coils or transformers 10, which may be of the ordinary 10 type, and in addition to these a second set of induction-coils 11 is employed, said second set being of the construction best shown in Fig. 4. 20 designates a suitable support, on which are arranged two fixed spools 21 and 15 22 and two movable spools 23 and 24 at each of the stations A, B, C, and D. The line-wire 6 is connected to the spool 21, and the line-wire 7 is connected to the spool 22. The windings of spools 21 and 22 extend in opposite directions, so that one will counteract the effect of the other. Lines 8 and 9 are 20 connected at stations C and D in a similar manner. The coils 23 and 24 are connected to the opposite sides of the secondary and 25 are to be wound, respectively, in opposite directions, and these two coils are adjusted independently of each other to vary the distance between them and the fixed coils at the ends of the support 20. The reason for using 30 the repeating-coils 10 is in order to increase the efficiency of the apparatus, the balancing-coils 11 being more or less separated or dissociated from one another will not be as efficient in transmitting as will the repeating-coils 10, which are intimately associated. In some cases where efficiency is of minor importance the repeating-coils may be dispensed with, as shown in Fig. 2. The repeating-coils as herein used are such as are 35 ordinarily used, the coils 11 being the coils which I employ for the purpose of obtaining the balancing effect above noted and for preventing cross-talk between the phantom circuit and the main circuit. Between the two 40 main circuits are phantom stations E and F, each including a transmitter 12, a battery 13, and an induction-coil 14, and the secondary of said induction-coil being connected by a wire 15 to the two main metallic circuits at 45 the points 16, and in order that conversation may be carried on between stations E and F without interfering with conversations between stations A and B or between stations C and D the movable coils 23 and 24 at each 50 station must be shifted or adjusted with reference to coils 21 and 22 at each station until there is silence in the receivers of stations A and B and stations C and D. This may be said to be establishing zero-potentials at the 55 point 16 and in the receivers of the stations A, B, C, and D. In this manner cross-conversation or other disturbing noises may be entirely eliminated between the stations E and F and the four other stations. It must 60 be understood that the movable coils are not 65

necessary for the operation of the superposed or phantom circuits, but are used to prevent the interference of the superposed or phantom circuits with the main or associated circuits and to prevent the main or associated 70 circuits from interfering with the superposed or phantom circuits. If the point of connection 16 is exactly at zero-potential, conversation can be carried on through the phantom circuit, and to obtain this balancing effect of 75 the opposite sides of the lines transformers or induction-coils (illustrated in Fig. 4) are employed. If there is less resistance on the wire 6 than on the wire 7, a stronger magnetic field will be created at the coil 21 than 80 is created at the coil 22, and for this reason the coil 23 should be adjusted to a greater distance from the coil 21 than coil 24 is separated from the coil 22. This alters the inductive relation between the main line and 85 the secondary.

The arrangement of the circuits may be altered to suit varying conditions, and in Fig. 2 is shown a system similar to that illustrated in Fig. 1, the auxiliary induction-coils 10 being omitted and a phantom circuit and its 90 telephones for stations being provided with induction-coils 11 of the character shown in Fig. 1.

In Fig. 3 is illustrated a system in which 95 three main lines 6, 7, and 9 are employed to form two metallic telephone-circuits, this being accomplished by connecting a third wire 9 into the two wires 6 and 7 of an all-metallic circuit, the two wires 6 and 7 of the all-metallic circuit forming in parallel one-half of the 100 second or superposed circuit.

Referring now to Fig. 1, the circuit between stations A and B is a complete metallic circuit, and conversation may be carried on in 105 the usual manner. The circuit-connecting stations C and D is also a complete metallic circuit. In order that conversation may be carried on between the phantom stations E and F without disturbing other stations, it is 110 necessary that the sides of the local circuits be balanced by proper adjustment of the coils 23 and 24. The wires 15 are connected to the metallic circuits at points of zero-potential relative to the local stations of the 115 mains, so that the wires 6 and 7 will be used in parallel as one conductor between phantom stations E and F. The two wires 8 and 9 will be used in parallel as the second or return conductor between stations E and F. 120 This makes a complete metallic circuit between stations E and F, and the current entering the wires 6 and 7 or 8 and 9 will split and traverse both lines in the same direction and again unite at the opposite end of this 125 double conductor. When arranged in this manner, it is found that conversation may be carried on between stations A and B or C and D and between E and F at the same time 130 without interfering with each other.

In carrying the invention into practice the spools 21 and 22 may be fixedly secured to a suitable support 20 and spools 23 and 24 may be fitted snugly thereon, so that when adjusted they will remain in position by virtue of friction against the support, or the coils 23 and 24 may be disposed in any suitable manner so that they can be adjusted relative to coils 21 and 22, respectively, or the spools 23 and 24 may be fixed and 21 and 22 may be movable. The repeating-coil 10 has two primary and two secondary windings. It will be noted that the adjustment of the coils permits the shifting of the point of zero-potential through a considerable range, this being accomplished by winding the primary and the secondary coils on separate spools, of which one may be bodily moved toward and from the other to any desired extent, while the support employed may be formed of wood or other non-metallic material.

Figs. 5 and 6 illustrate my invention applied to multiple connections. In Fig. 5, A', B', C', and D' designate four stations, at each of which is a transmitter 36, a battery 38, and a primary 46 and secondary 41 of an induction-coil, all similar to the corresponding elements in Fig. 1. The secondary 41 includes a receiver 37, arranged as in Fig. 1. Between stations A' and B' extend main lines 30 and 31, and between stations C' and D' extend main lines 47 and 48. The connection between each secondary and the main line is formed by the repeating-coils 40 and in addition to these a second set of induction-coils 49. 50 designates a support for the fixed spools 32 and 33 and two movable spools 34 and 35. The line 30 is connected to station A' at a point 43 between coil 32 and the secondary of repeating-coil 40, and line 31 is connected at a point 42 between spool 33 and the secondary of repeating-coil 40, thus allowing currents passing over line 30 to pass through the repeating-coil 40 and the fixed spools 32 and 33 of coils 49 in multiple, returning on line 31. The effect of this operation on the local stations of the mains and of phantom stations E' and F' is similar to that described of the elements shown in Fig. 1. The manner of wiring may be varied, and the number of movable induction-coils may be varied. In Fig. 6 is shown a station provided with a repeating-coil 51, line-wires 52 and 53, fixed coils or spools 54 and 55, and one movable coil 56, and a switchboard pair of lines similar in operation to the operations of lines 57 and 58 of the local stations shown in Fig. 5. The difference between the multiple connection and the series connection is that the switchboard pair in the multiple is connected as follows: Wire 58 is connected at a point 43', which is a point between spool 34 and the primary of repeating-coil 40, and wire 57 of secondary 41 is connected at a point 42', which is a point be-

tween spool 35 and the primary of repeating-coil 40, which is commonly known as a "multiple" connection. In the series connection the phantom circuit goes through the fixed or repeating coil 40 and the fixed coils 32 and 33 of the induction-coils 49. Another difference is that in the multiple connection the fixed or repeating-coil 40 may be opened without opening the circuit of the induction-coil 49, and vice versa, whereas in the series connection opening the fixed or repeating coil 40 would open also the induction-coils 49. One advantage of using the multiple connection of these coils is that the phantom circuit does not have to pass through the fixed coil 40. Hence it is not necessary for the fixed coil 40 to be absolutely differential. Another advantage is that much resistance is removed from the path of the phantom circuit. Another advantage is that the fixed or repeating coil 40 does not react on the movable coil 34 and 35—that is, the current generated in the secondaries of the fixed or repeating coil 40 does not have to pass through the movable coils 34 and 35, and therefore has no reaction on the primary of the movable coil 34 and 35, and vice versa.

One of the advantages of this invention is that it is readily applicable to circuits already in use, and the number of circuits in any group of circuits can be doubled, less one, to a reasonable extent.

Various other changes than those noted above may be made without departing from my invention. For instance, either of the coils of either set may be movable with respect to the other two, and any means may be employed to lessen or increase the effect of one coil upon the other at either side of the circuit.

Having fully described my invention, what I claim as new, and desire to secure by Letters Patent, is—

1. In a telephone system, main circuits provided with local circuits, phantom circuits connected to said main circuits at points of approximately equal potential, and inductive means for causing silence in the receivers of said local circuits whereby cross-conversation and disturbances between said main circuits and phantom circuits are eliminated.

2. In a telephone system having main circuits provided with local circuits, phantom circuits connected to said main circuits at points of approximately equal potential, and induction-coils composed of a plurality of windings operatively connected in said main and local circuits and capable of adjustments from and toward each other whereby points of zero-potential may be located in said local circuits.

3. In a telephone system provided with main metallic circuits having local circuits, superposed or phantom circuits in combina-

tion with said main metallic circuits, and adjusting devices consisting of coils movable toward and from each other for preventing cross-induction between said superposed or 5 phantom circuits and the local circuits of said main metallic circuits.

4. In telephony, the combination with all circuits, of local circuits arranged in inductive relation to the metallic circuits, sets of 10 balancing-coils wound on separate spools and disposed, two of each set being in the metallic and the others in the local circuits, the spools of the local circuits being adjustable with relation to the metallic circuits, and 15 phantom circuits connected to the metallic circuits at points of zero-potential.

5. In telephony, local circuit having windings arranged in multiple, metallic mains having windings also connected in 20 multiple, the coils of one set of windings being bodily adjustable with respect to the coils of the other set and serving to balance both sides of the local circuits, and phantom circuits connected to the mains at points of zero- 25 potential.

6. A telephone system comprising metallic circuits provided with repeating-coils, inductive coils composed of movable and fixed 30 spools connected to said repeating-coils, said movable spools being disposed in inductive relation to said fixed spools, locals including secondaries connected to said movable spools,

and phantom circuits connected to said metallic circuits and provided with local circuits.

7. Local stations including secondaries, mains arranged in inductive relation thereto, a support, fixed coils carried by the support and connected with the mains, adjustable coils connected in the secondaries, and a 40 phantom circuit connected to the mains at point of zero-potential.

8. In a telephone system having main metallic talking-circuits, and repeating-coils 45 therein at stations, of phantom talking-circuits connected to said main circuits, a coil interposed in each limb or side of said main circuit, one or more coils inductively disposed with relation to the latter coils and connected in the local talking-circuits of said main 50 circuits, and means for varying the inductive effect of one of the said coils upon the other at either side of the main circuit, whereby high efficiency of the apparatus is maintained as well as cross-talk and disturbing noises 55 between the main and phantom stations prevented.

In testimony whereof I set my hand, in the presence of two witnesses, this 20th day of September, 1904.

THOMAS P. JORDAN.
